UNITED STATES PATENT OFFICE.

FERDINAND R. WOLTER, OF MINNEAPOLIS, MINNESOTA.

MOP-WRINGER.

1,360,485.

Specification of Letters Patent. Patented Nov. 30, 1920.

Application filed May 21, 1918. Serial No. 235,759.

To all whom it may concern:

Be it known that I, FERDINAND R. WOLTER, a citizen of the United States, residing at Minneapolis, in the county of Hennepin 5 and State of Minnesota, have invented certain new and useful Improvements in Mop-Wringers; and I do hereby declare the following to be a full, clear, and exact description of the invention, such as will enable 10 others skilled in the art to which it appertains to make and use the same.

My invention has for its object to provide an improved so-called mop wringer, and to such ends, generally stated, the invention 15 consists of the novel devices and combinations of devices hereinafter described and defined in the claims.

The salient novelty of the invention is found in improved means for adjustably and 20 yieldingly pressing the one roller against the other, but the invention involves certain other highly important though minor novel features which either improve the action of the device, or facilitate the manufacture 25 thereof.

In the accompanying drawings which illustrate the invention, like characters indicate like parts throughout the several views.

Referring to the drawings, 30 Figure 1 is a plan view of the improved mop wringer;

Fig. 2 is a fragmentary section on the line 2—2 of Fig. 1;

Fig. 3 is a fragmentary detail of certain 35 parts found in the vicinity of the line marked 3—3 on Fig. 1;

Fig. 4 is a vertical section taken through the device on the line 4—4 of Fig. 1, some 40 parts being broken away and some parts being found in full; and

Fig. 5 is a detail with some parts in elevation and some parts sectioned on the line 5—5 of Fig. 4.

The wringer is supported on a pail which 45 is preferably a cylindrical sheet metal structure indicated, as an entirety, by the numeral 6, the same having the customary beaded upper edge. The lower edge or bottom of the pail is telescoped into an endless 50 steel or iron hoop 7. This hoop is provided with a plurality of outwardly pressed tapered corrugations 8 that are formed with inwardly pressed lips 9, the said corrugations 8 preferably do not run completely to the upper edge of the hoop and are preferably made flaring in a downward projec-

tion, that is, are given an increasing horizontal dimension toward the lower edge of the hoop. This, while it gives the corrugations an outward flare, contracts the lower edge of 60 the hoop without contracting the upper edge of the hoop. The pail is tightly pressed into the tapered hoop until its bottom strikes the stop lips 9 as shown in Fig. 5. The hoop will then be firmly held in position. At 65 several places, preferably at diametrically opposite points, the hoop is formed with slightly outpressed portions 9^a into which the upper ends of a pair of foot brackets 10 are inserted. The outer ends of these brackets 10 rest upon the floor and are adapted to be stepped on by the operator to hold the pail positively anchored to the floor when pulling upward on the mop.

Fitted into the upper edge portion of the 75 pail is an approximately rectangular roller supporting frame preferably made from a flat steel bar bent to form parallel sides 11, a cross connecting portion 12 and short segmental portions 13 and 14. The segmental 80 portions 13 and 14 fit the inner surfaces of the pail and are adapted to be rigidly but detachably secured to the pail by short nut-equipped bolts 15. The side bars 11 of the said frame are set, preferably edgewise, 85 while the cross portion 12 is preferably turned edgewise into a horizontal position. The numeral 16 indicates a short transverse spacing bar, the ends of which are interposed 90 between the pail and the segmental end portions 14 and are secured by the said nuts 15.

The relatively fixed and movable rollers are indicated, respectively, by the numerals 17 and 18. The trunnions 17^a of the roller 17 are journaled in bearing blocks 19 while 95 the trunnions 18^a of the movable roller 18 are journaled in bearing blocks 20. These bearing blocks 19 and 20 are grooved to fit the side bars 11 of the roller supporting frame. The said bearing blocks 20 are free 100 to slide on the said bars 11 while the bearing blocks 19 are provided with dowel-like projections 21 that engage perforations 22 in the bars 11, and thereby hold the blocks 19 and rollers 17 fixed or against sliding 105 movement on the said bars. The sliding bearing blocks 20 are provided with sleeve-like hubs 20^a in which the trunnions 18^a are directly journaled, and these hubs are provided, each with a key lug 20^b. The said key lugs 20^b are provided with intermediate notches that leave smooth cylindrical hub

portions upon which the end prongs 23^a of the yoke-like operating levers 23 are pivotally mounted. To permit the prongs 23^a to be thus applied on the smooth portions of the said hubs 20^a, said prongs are provided with notches 23^b, through which the outer portions of the keys 20^b may freely pass when the said lever, in the act of assembling or dismounting, is turned over into an extreme position, to wit, into a position about 175 degrees to the right from that position shown in Fig. 3.

After the yoke-like operating lever is applied, as stated, an angle iron cross connecting tie bar 24 is applied thereto, as best shown in Fig. 1, preferably by means of short nut-equipped bolts 24^a.

To the intermediate portion of the arms of the yoke-like lever 23, a sort of a yoke-like stirrup 25 is pivotally connected, preferably by loosely applied rivets 26. These rivets, instead of being upset at their ends, are left free for application and removal and the rivets are simply held in position detachably by means of spring fingers 27. These springs 27 are preferably made of spring wire, each having one end passed through a perforation in the adjacent arm of the lever 23 and clenched against the same, while the free end of said spring is inserted into the notched or slotted heads of the coöperating rivet. This makes assembling of the parts and dismounting or disconnection thereof, a very easy matter, and, moreover, is cheap construction.

The so-called stirrup 25 is preferably formed integral with, or otherwise rigidly secured to a thrust bolt 28, the free end of which is flattened and provided with a longitudinal slot 29. This slotted end of the thrust bolt 28 is slidably pivoted to an anchoring bracket 30 detachably secured by a short-nut-equipped bolt 31 (see Fig. 2) to the transverse bar 12 of the roller supporting frame. Working slidably on the flattened end of the thrust bolt 28, but held against rotation thereon, is an externally threaded spring adjusting sleeve 32, the outer end head of which is spring pressed against the head of the anchoring bracket 30 and which head, it will be noted by reference to Fig. 4, has a flattened oblique upper edge surface 30^a for an important purpose presently to be noted.

Working with threaded engagement on the sleeve 32 is a spring adjusting nut 33 preferably having a knurled surface so that it may be readily turned by the hand. A strong coiled spring 34 surrounds the thrust bolt 28 and sleeve 32 and is compressed between the stirrup 25 and the adjusting nut 33.

The numeral 35 indicates guard rods that extend parallel to but inward of the side bars 11 immediately below the rollers 17

and 18 and serve to prevent the mop cloth from getting caught at the end of the rollers. The ends of these guard rods 35 are bent at an angle, passed through perforations in the segmental portions 13 and 14 of the 70 roller supporting frame and are seated in small outpressed pockets 36 formed in the sides of the pail. These guard rods may, therefore, be easily sprung into and out of working position.

The yoke-like lever 23 can be applied to or disconnected from the sleeve-like hubs 20 only, as before stated, it is turned about 175 degrees to the right into position shown in Figs. 3 and 4. Here it will be noted that this movement cannot take place as long as the said lever is pivotally connected at 26 to the stirrup 25 of the plunger 28. Hence, there is no danger of accidental disconnection.

The plunger or thrust bolt 28 and its stirrup 25 act as one member of a toggle, the other member of which is afforded by the lever 23, the said two toggle members being connected by rivet-like studs 26. This toggle is operated by hand force applied to the projecting free end of the lever 23, and when the toggle is set, as shown in Figs. 1, 3 and 4, it will be noted that the axis of its intermediate pivot at 26 is slightly below the dead center and the projecting end of the lever 23 is then pressed downward against the rim of the pail, thereby locking the toggle and locking the two rollers, pressed the one toward the other. Of course, the spring 34 makes one of the toggle members yielding so that the rollers will adapt themselves to the mop cloth compressed between the same. The tension of the spring, obviously, may be varied by adjustments of 95 the nut 33. When the toggle is in its locked position noted, the end of the sliding sleeve 32 bears against the front inner surface of the head of the so-called anchoring bracket 30. When the free outer end of the lever 116 23 is raised slightly, so as to carry the intermediate pivot 26 of the toggle above its dead center, then the force of the compression on the mop cloth will give an initial separation to the rollers and an initial further 115 buckling movement to the toggle, but such force would not buckle the toggle beyond the point where the pressure on the mop cloth was raised. The completion of the buckling movement of the toggle is produced by the action of the spring 34 in pressing the head of sleeve 32 against the flattened surface 30^a of the head of bracket 30, and under such action, the toggle will be buckled to its extreme position shown by 125 dotted lines in Fig. 4 and the movable roller 18 will be retracted, thereby to its extreme position, also shown by said dotted line. This insures a wide opening between the two wringer rollers, so that the mop cloth may 130 .

be freely drawn downward between the same and into the water containing pail. Of course, by compression in the toggle required to set the rollers wringing action is produced simply by forcing the free end of the lever 23 downward and back to its full line position, Figs. 1 and 4.

The efficiency of this device has been thoroughly demonstrated in practice. It is not only efficient in operation, but strong and durable and capable of being manufactured at reasonably small cost, because all of the various parts are designed to be made at a minimum of cost and to be assembled with a minimum of labor.

What I claim is:

1. The combination with a pail and a roller supporting frame mounted on the rim thereof, of coöperating rollers journaled 20 on said frame, one of which is movable toward and from the other, a toggle having a base of re-action on said frame and connected to said movable roller for operating the same, the said toggle including a spring 25 element, and a spring tension adjusting device.

2. The combination with a pail and a roller supporting frame connected to the rim thereof, said roller support having laterally spaced parallel side bars, relatively fixed and 30 slidable roller bearings on said side bars, coöperating wringer rollers journaled to said fixed and movable slidable roller bearing, a yoke-like lever having prongs pivoted to said 35 slidable bearings, a thrust bolt having a pivotal connection to the intermediate portions of the prongs of said yoke-like lever and therewith constituting a toggle, an anchor bracket on the rim of the pail serving 40 to guide said thrust bolt but permitting endwise movements thereof, and a coiled spring on said thrust bolt reacting against the same and against said anchor bracket.

3. The combination with a pail and a 45 roller supporting frame connected to the rim thereof, said roller support having laterally spaced parallel side bars, relatively fixed and slidable roller bearings on said side bars, coöperating wringer rollers journaled to said

fixed and movable slidable roller bearings, 50 a yoke-like lever having prongs pivoted to said slidable bearings, a thrust bolt pivoted to the intermediate portions of the prongs of said yoke-like lever and therewith constituting a toggle, an anchor bracket on the 55 rim of the pail serving to guide said thrust bolt but permitting endwise movements thereof, a coiled spring on said thrust bolt reacting against the same and against said anchor bracket, means for adjusting the tension of said spring comprising a non-rotary externally threaded sleeve slidable on said thrust bolt and engageable with said anchor bracket, and an adjusting nut on said sleeve directly engaging one end of said spring, 60 the toggle formed by said thrust bolt and lever being movable to a position slightly beyond a dead center to set the coöperating rollers for wringing action.

4. The combination with a pail, of a roller 70 support including parallel laterally spaced bars secured to the rim of the pail, relatively fixed and slidable roller bearings applied on said side bars, relatively fixed and movable wringer rollers journaled to said fixed and 75 slidable bearings, said slidable bearings having hubs with projecting key lugs, a yoke-like lever having prongs pivoted on the hubs of said slidable bearings and having lug entrance notches adapting the said prongs to 80 be applied to or removable from said hubs when said lever is turned into a predetermined extreme position, an anchor bracket on the rim of the pail, a thrust bolt slidable through said anchor bracket and provided 85 with a stirrup-like end pivoted to the intermediate portions of the sides of said yoke-like lever, and a spring on said thrust bolt reacting against its stirrup end and against said thrust bracket, the said yoke-like lever 90 and thrust bolt constituting a toggle for operating said movable roller.

In testimony whereof I affix my signature in presence of two witnesses.

FERDINAND R. WOLTER.
